GRINDING WHEEL DRESSER

Cecil M. Griffin, Pittsburgh, Pa.

Application April 9, 1948, Serial No. 19,917

14 Claims. (Cl. 125—11)

1

This invention is for a grinding wheel dresser, and relates particularly to contour dressing of grinding wheels; wherewith a diamond or similar hard point is utilized to dress or shape the periphery of a grinding wheel.

In making precision punches and form tools, and various machine parts, which require accurate grinding of various radii and angles, a means of readily and accurately dressing the grinding wheel to the various radii and angles is of paramount importance.

The present invention has for its object to provide an improved grinding wheel dresser of simple and relatively inexpensive construction, that is easy to operate and maintain, and will smoothly and accurately dress both radii and angles, including 180° concave radii; and that also incorporates a means of easily accomplishing the important feat of dressing a radius and two tangents to the same at one continuous operation. Moreover my invention provides a dresser which may be used in either a horizontal or up-ended vertical position, so as to adapt it to use on different types of grinding machines for different dressing operations.

According to the present invention, the diamond is interposed near the center of a comparatively long, carrying frame having its supporting bearings at its extremities. With this arrangement a "between centers" effect is attained which enhances smooth operation. Furthermore, the sidewise angles dressing movement is effected by swinging one end of the carrying frame about the bearing at the other end as a pivot, thus in the angles cutting operation, too, the diamond is interposed between widely spaced bearings, resulting in smooth, accurate dressing; and, furthermore, my invention obviates the need for close-fitted, dove-tailed or ball bearing slides, which are difficult to maintain, particularly in the presence of the grit incident to grinding operations.

My invention may be more fully understood by reference to the accompanying drawings, in which:

Fig. 1 is a top plan view of a tool embodying my invention;

Fig. 2 is a side elevation of the tool shown in Fig. 1, with parts thereof shown in section;

Fig. 3 is an end view of the tool shown in Fig. 1;

Fig. 4 is a transverse vertical section in substantially the plane of line IV—IV of Fig. 2;

Fig. 5 is a side elevation, also partly in section, of one end of the device, but viewed from the opposite side from Fig. 2;

2

Fig. 6 is a detail view of one mounting for the dressing point, this mounting being particularly designed for use in dressing concaved surfaces of extremely small radii;

Fig. 7 is a side elevation of another mounting for the dressing tool; and

Fig. 8 is a top plan view of the part shown in Fig. 7.

Referring to the drawings, the dresser comprises a supporting base frame 2, having a flat bottom surface so that it can be conveniently set on the table of a grinding machine. It has upward extending support portions 3 and 4 at the ends thereof constituting head-stock and tail-stock portions, respectively, rigidly carried on the support 3 is a fixed dial 5 having a generally semi-circular periphery. The dial is graduated in degrees having 0 at the top center, and extending through a range of 90 degrees in each direction, as best shown in Figure 3. Passing through the support 3 is a sleeve or spindle 6. Rigidly attached to the inner end of this sleeve is a cross rail 7. The cross rail 7 is provided at each end with an upwardly-extending arm 8, each arm being bent forwardly at 8a over the periphery of the dial 5. The two forwardly-bent portions 8a are connected by a cross bar 9. This cross bar has a depending finger 10 at the center thereof which is rigidly attached thereto. Attached to the depending finger is an indicator 11 which moves in a groove 5a concentric with the graduations on the face of the dial. The indicator 11 may itself be graduated so as to provide a vernier for accurately determining fractional degrees of rotation. Because of the sleeve being rotatable in the support 3, the cross rail 7, which is horizontal when the rotation indicator 11 is at 0 on the dial 5 may be tilted 90° in either a clockwise or anti-clockwise direction from the horizontal, the cross bar providing a convenient handle for so manipulating the device. In Fig. 3 the dotted lines show this part of the structure which has just been described, tilted from the horizontal position in a clockwise direction 54°. The purpose of this arrangement will be hereinafter more fully described.

Inside the sleeve or spindle 6 is a shaft 12 having a graduated operating dial 13 on its outer end, and a toothed pinion 14 on its inner end, so that when the dial 13 is turned, the pinion 14 will be rotated. The pinion 14 is in mesh with the rack 15 on the under side of a plate 16, which overhangs the rail 7, and, through the gliders 16a, is slidably supported by rail 7 and

The plate 16 is at the top of one arm 17 of a cradle-like carrier frame having a horizontal connecting bar 18 and another upwardly-extending arm 19. The arm 19 has a forwardly-protruding stud element 20 near its upper end terminating in a hemispherical bearing portion which is seated in the socket element 21 on the upright 4 of the base 2, providing a universal pivotal bearing for that end of the carrier frame. A leaf spring finger 22 secured to the upright 4 has its free end interposed in a groove in the stud member 20 to keep the hemispherical bearing seated in the socket 21.

By reason of the arrangement just described, rotation of the dial 13 turns the pinion 14 and transmits motion to the rack 15 to move the right-hand end of the underslung frame as viewed in Fig. 2, back and forth transversely of the shaft 12, the gliders 16a sliding along the top surface of the rail 7. Thus one end of the frame may be swung back and forth about the bearing 20-21 as a pivot point and transversely to the axis of rotation of the shaft 12. The upright arm 17 of the underslung pivoting frame is provided with an extension 23 that supports a leaf spring 24 having a roller 25 thereon which bears against the under side of the rail 7 to keep the gliders 16a in contact with the upper face of the rail.

The cross rail 7 has a fixed keeper 26 secured thereto, and a rod 27 is slidable back and forth in this keeper. The rod 27 as viewed in Fig. 4, together with the rectangular block 28 and the post 29 are rigidly assembled as one piece. The post 29 is in a position to stop against the pin or abutment 30 in the cross rail 7, and, also, to contact the plate 16, through the adjusting screw 29a. A tension spring 31 has one end secured to the top of the post 29, and has its other end secured to a stud 32 at that edge of the plate 16 which is most remote from the post 29. Spring 31 thus exerts a tension tending to pull the plate 16 toward the left as viewed in Fig. 4, or toward the top as viewed in Fig. 1, to normally hold its edge in contact with the adjusting screw 29a. When the dial 13 is rotated in a direction tending to move the plate 16 toward the right as viewed in Fig. 4, the spring 31 is put under added tension because the point 32 moves away from the post 29. Consequently, when the knob 13 is released, the spring 31 will act to pull the plate 16 back against the screw 29a.

A second tension spring 34 extending under the plate 16, also has one end secured to the post 29. The other end of this spring 34 is anchored to a stud 36 on the rail 7. The spring 34 thus operates so that if the dial 13 is turned in the opposite direction, i. e., in a direction to move the plate 16 to the left as viewed in Fig. 4, the spring 34 will act to restore it to the center position. The spring 34 cannot pull the plate 16 in the opposite direction past the center position because of the post 29 contacting the stop 30.

Springs 31 and 34, therefore, operate to normally keep the swinging frame centered.

Adjusting screw 29a is provided as a means of compensating for wear of post 29 against stop pin 30, so the diamond hereinafter described may be kept centered in the plane which is perpendicular to the rail 7 and contains the axis of rotation of the "underslung frame." This is a condition that must maintain if the radius dressed is to be the same as the measured setting of the diamond above or below the axis of rotation.

The diamond dressing point 44, supported in the manner hereinafter described, is carried by a

vertically adjustable cross bar 40 mounted in the pivoted underslung frame. This bar has hand screws 41 at each end for operating clamping blocks 42 (see Fig. 1) by means of which the ends of the bar are clamped to the ends of the frame to secure it in position.

Adjustment of the diamond toward or from the pivotal axis of the carrier, for large or small radii, is accomplished by moving the cross bar 10 40, which may be moved upward or downward along the uprights 17 and 19 (see Fig. 2) of the underslung rotating frame when the clamps 42 have been slackened by loosening the hand screws 41. The hand screws 41 pass loosely through the cross bar 40 and are threaded in the clamps 42. Thus by tightening the hand screws 41 the cross bar 40 is drawn against the faces of the uprights 17 and 19, the faces of the uprights 17 and 19 being parallel to the aforesaid plane, in which the diamond is centered (the plane which is perpendicular to the rail 7 and contains the axis of rotation of the "underslung" frame).

Jack screws 43a are provided to facilitate accurate positioning of bar 40. These jack screws 25 are threaded through pins 43, which are interchangeable in the vertical series of holes in the uprights 17 and 19. When the desired adjustment of the bar 40 moves it beyond the range of the jack screws, pins 43 are placed in higher or lower holes, as the case requires.

The dressing point itself is designated 44, and in the form of the invention shown in Figs. 1 to 6, it is set in a supporting bar 45, the ends of which are secured to the arms of a U-shaped yoke 46, the yoke 46 being rigidly secured to bar 40 by screws 47.

The bar 45, in which the diamond is set (see Figs. 1, 2 and 6) is of decreasing diameter from its ends toward the diamond. This reduced diameter is necessary only in dressing small concave radii, particularly when the angle turned is large, as in dressing small 180° concave radii.

For dressing larger concave radii and all convex radii, a diamond supporting bar of uniform cross section throughout may be used. Also the bar 57 (see Figs. 7 and 8) in which the diamond 55 is set in the top of a post 56 may be used. It will be seen that the post 56 is tilted (10° to 15°) from the perpendicular, and also, that by loosening the clamping screw 58 the post 56 may be rotated. This tilted position, together with the rotatability, permits presentation of a new cutting edge when the diamond becomes dull, thus prolonging the effective life of the diamond. The bar 57 is interchangeable with the bar 45 shown in Fig. 6. A slit milled in the bar 57 (see Fig. 8) permits loosening the post 56 when screw 58 is unscrewed, making it easy to adjust or remove the post.

The ends of the bar 57, like the ends of the bar 45, are cut away to the center line of the bar, as indicated at 57a, so that the plane of the faces 57a contains the diamond point. This is done as a means of accomplishing interchangeability.

To facilitate the operation in dressing angles and tangents to radii, stops are provided comprising the rectangular base pieces 50; the clamping screws 51 with wrenching handles 52, and the posts 53 which protrude from the base pieces 50, to engage the dependent finger 10.

To set a stop the indicator 11 is brought to the desired angular position on dial 5 and held there by using the bar 9 as a rotating handle or crank, then the part 50 is rotated about the clamping screw 51 until the post 53 is brought against the

finger 10. The clamping screw is then tightened firmly by turning it with the lever 52. The post 53 is thus held in its position, where it arrests the radius dressing rotation when the finger 10 comes against it.

Fig. 3 shows the clockwise stop set to arrest the radius dressing operation at 54°, as it would be set to dress an angle of 54° or to dress a tangent to a radius at an angle of 54°.

To dress two angles or two tangents, or an angle inclined anti-clockwise to the horizontal, the other (left-hand) stop is set, using the same procedure as is outlined for setting the clockwise stop.

From the foregoing it will be seen that in addition to relatively simple and rugged construction, my invention provides a dresser having important inherent features which enhance its usability, which are:

(1) The diamond point sets in the side of its supporting bar 45, which is, in turn, rigidly supported at both ends, and is arranged in a tangent position to the grinding wheel, which permits dressing deep concave radii (up to 180°) without requiring a special attachment. This construction also provides a maximum of rigidity and accuracy of alignment for the diamond point which is particularly important in dressing very small concave radii.

(2) Dials are positioned where they are "out of the dirt," i.e., are not sprayed by the grit incident to the dressing operation, and where they do not interfere when using the dresser in cramped quarters, permitting use of large dials, which are easy to read and operate.

(3) The bearing support 4, which may be made to serve as a base, permits the dresser to be used in either a horizontal position, under the grinding wheels, as is shown in the drawings, or up-ended for use in front of the wheel, thus making my dresser readily useable on a wide range of different types of grinding machines.

While I have illustrated and described a specific embodiment of my invention, it will be understood that this is by way of illustration, and that various changes and modifications may be made in the construction and arrangement of parts within the contemplation of my invention, and under the scope of the following claims.

I claim:

1. A radius and angle dresser for grinding wheels comprising a base with upright head-stock and tail-stock portions at its ends containing bearing systems, said bearing systems having a common axis for rotation, said head-stock bearing system supporting a rotatable spindle in rigid alignment, a portion of the spindle projecting from the inner face of the head-stock, a rail rigidly attached crosswise of said spindle projection and rotatable with the spindle, a rotatable carrier frame extending between the rail and the tail-stock, a cutting nib adjustably mounted on the carrier frame intermediate the ends thereof, means connecting the carrier frame to the rail providing for coincidental rotation of the frame and the rail and also for sidewise movement of the end of the carrier frame along the rail to effect angular displacement of the carrier frame about its pivot axis in the tail-stock bearing system, said tail-stock bearing system functioning to provide support for the carrier frame in both rotational and angular displacement, a graduated scale on the headstock, handle means attached to the rail for rotating the rail and the carrier having an indicator thereon terminating adjacent said scale, a knob outside of the head-stock, cooperating means actuated by the knob and connected with the carrier for effecting angular movement of the carrier, and adjustable stops on the head-stock in the path of movement of said handle for limiting the rotational movement of the carrier in either direction.

2. A radius and angle dresser for grinding wheels as described in claim 1, wherein the cutting nib is set in the side of a rod, the rod being supported at its ends, that portion of the rod between the supports being in clear suspension, the cutting nib being set in the suspended portion of the rod, the longitudinal axis of the rod being parallel to the axis of rotation of the carrier frame.

3. A radius and angle dresser as defined in claim 2, wherein the suspended portion of the rod, in which the cutting nib is set, is of decreased diameter to permit dressing small, deep, concave radii.

4. A radius and angle dresser as defined in claim 3, wherein the bottom and the tail-stock end of the base are flattened so the dresser will stand securely on a flat surface in either a horizontal or a vertical position.

5. A radius and angle dresser as defined in claim 4, a centering stop on said carrier frame supporting means, spring means resisting movement of the carrier frame along the rail from, and automatically returning it to, said centering stop, and adjusting means on said stop to adjust the centered position of the carrier frame thereby to accurately align the cutting nib in the plane perpendicular to its plane of sidewise movement and containing the axis of rotation.

6. A radius and angle dresser for grinding wheels comprising a base with upright head-stock and tail-stock portions at its ends containing bearing systems, said bearing systems having a common axis for rotation, said head-stock bearing system supporting a rotatable spindle in rigid alignment, a portion of the spindle projecting from the inner face of the head-stock, a rail rigidly attached crosswise of said spindle projection and rotatable with the spindle, a rotatable carrier frame extending between the rail and the tail-stock, a cutting nib adjustably mounted intermediate the ends of the carrier frame, means connecting the carrier frame to the rail providing for coincidental rotation of the frame and the rail and also for sidewise movement of the end of the carrier frame along the rail to effect angular displacement of the carrier frame about its pivot axis in the tail-stock bearing system, said tail-stock bearing system functioning to provide support for the carrier frame in both rotational and angular displacement, a graduated scale on the headstock, handle means attached to the rail for rotating the rail and the carrier having an indicator thereon terminating adjacent said scale, a knob outside of the head-stock, cooperating means actuated by the knob and connected with the carrier for effecting angular movement of the carrier, and adjustable stops on the head-stock in the path of movement of said handle for limiting the rotational movement of the carrier in either direction.

7. A radius and angle dresser for grinding wheels comprising a base with upright head-stock and tail-stock portions at its ends containing bearing systems, said bearing systems having a common axis for rotation, said head-stock bearing system supporting a rotatable spindle in rigid alignment, a portion of the spindle projecting from the inner face of the head-stock, a rail rigidly attached crosswise of

said spindle projection and rotatable with the spindle, a rotatable carrier frame extending between the rail and the tail-stock, a cutting nib adjustably mounted intermediate the ends of the carrier frame, means connecting the carrier frame to the rail providing for coincidental rotation of the frame and the rail and also for sidewise movement of the end of the carrier frame along the rail to effect angular displacement of the carrier frame about its pivot axis in the tail-stock bearing system, said tail-stock bearing system functioning to provide support for the carrier frame in both rotational and angular displacement, a graduated scale on the head-stock, handle means on the rail for rotating the rail and the carrier having an indicator thereon terminating adjacent said scale, a knob outside of the head-stock, cooperating means actuated by the knob and connected with the carrier for effecting angular movement of the carrier, adjustable stops on the head-stock in the path of movement of said handle for limiting the rotational movement of the carrier in either direction, the carrier frame being underslung, comprising a bar portion having an arm at each end thereof, a cross bar adjustably supported on said arms for movement radially to the axis about which the carrier frame rotates, and a cutting nib mounted on said bar.

8. A radius and angle dresser as defined in claim 7 wherein the cutting nib is mounted intermediate the ends of a rod, the rod having arms at each end thereof which in turn are secured to said cross bar.

9. A radius and angle shaping device comprising, in combination, a base with a head-stock part and a tail-stock part, thereon, said head-stock and tail-stock parts each containing a bearing system for lending pivotal support, said bearing systems being aligned to have a common pivotal axis, a spindle rotatably supported in the head-stock bearing system, a rail fixed to and rotatable with the spindle and extending crosswise said pivotal axis adjacent the inner face of the head-stock, a cradle-like carrier comprising a bar with upturned ends extending between and supported by the rail and the tail-stock bearing system, means connecting the carrier to the rail for holding them together for rotation as one and permitting sidewise movement of the end of the carrier along the rail to effect angular displacement of the carrier about a pivot axis in the tail-stock bearing system, said tail-stock bearing system functioning universally to provide support for the carrier in both rotational and angular displacement, a cutting nib mounted on the carrier intermediate the ends thereof, a graduated dial attached to the head-stock, a pointer connected by rigid interconnecting means to the rail and arranged to move along the dial graduations when the carrier is rotated to indicate the degree of rotation of the cutting nib, means operatively connected to the carrier for producing the side-to-side movement of the end of the car-

rier along the rail, an abutment pin on the rail, means acting in conjunction with the abutment pin to yieldably resist the side-to-side movement for arresting and holding the carrier at central position when side-to-side actuating forces are relinquished during radius shaping operations.

10. A radius and angle shaping device as defined in claim 9 wherein the cutting nib is mounted on a bar which extends between and is adjustably supported at its ends for up and down adjustment on the upturned ends of the cradle-like carrier, whereby adjustment of the cutting nib toward and from the axis of rotation of the carrier is effected.

11. A radius and angle shaping device as defined in claim 10 wherein the cutting nib is set in the side of a relatively slender rod which is connected at its ends only to the adjustably supported bar and held in spaced relation above the bar.

12. A radius and angle shaping device as defined in claim 9 wherein the means for centering and holding the carrier at central position comprises two tension springs and a movable member with one end of both attached to the movable member and both springs exerting force on said movable member in substantially the same direction, the other ends of the two springs being attached one to the rail and the other to the carrier the movable member stopping against the abutment pin when the carrier is at central position.

13. A radius and angle shaping device as defined in claim 9 wherein said rigid interconnecting means between the rail and the pointer comprises arms which extend from the rail over the periphery of the dial where they are connected with a member which extends across the face of the dial and lends support for the pointer and wherein said arms and connected member are so arranged to serve as a manipulable handle for rotation of the carrier.

14. A radius and angle dresser as defined in claim 13 wherein there are adjustable stops arranged to arrest the rotational movement at any predetermined degree of rotation, there being one stop to arrest the clockwise rotation and another to arrest the counterclockwise rotation.
